US0D1113211S

(12) **United States Design Patent** (10) Patent No.: **US D1,113,211 S**
(45) Date of Patent: ** Feb. 17, 2026

(54) **CHAIR**

(71) Applicant: **Andreu World Design, S.A.**, Chiva
(ES)

(72) Inventor: **Patricia Urquiola**, Valencia (ES)

(**) Term: **15 Years**

(21) Appl. No.: **35/520,645**

(22) Filed: **Apr. 21, 2023**

(80) **Hague Agreement Data**

Int. Filing Date: **Apr. 21, 2023**

Int. Reg. No.: **DM/228760**

Int. Reg. Date: **Apr. 21, 2023**

Int. Reg. Pub. Date: **Apr. 26, 2024**

(51) **LOC (15) Cl.** **06-01**

(52) **U.S. Cl.**

USPC **D6/364**

(58) **Field of Classification Search**

USPC D6/334, 335, 349, 363–365, 371,
D6/373–375, 377, 381

See application file for complete search history.
